W. E. WALDO

GAS OUTFIT

Filed June 14, 1922

Patented Feb. 10, 1925.

UNITED STATES PATENT OFFICE.

WILLIAM E. WALDO, OF TOLEDO, OHIO, ASSIGNOR OF ONE-HALF TO SAMUEL E. STARR,
OF TOLEDO, OHIO.

GAS OUTFIT.

Application filed June 14, 1922. Serial No. 568,104.

To all whom it may concern:

Be it known that I, WILLIAM E. WALDO, a citizen of the United States of America, residing at Toledo, Lucas County, Ohio, have 5 invented new and useful Gas Outfits, of which the following is a specification.

This invention relates to gas generating outfits.

This invention has utility when embodied 10 as a brazing or soldering gas installation from the fluid fuel source, having more particular adaptation as a piece of dental equipment.

Referring to the drawings:—

Fig. 1 is a side elevation of a portable liquid fuel gas generating outfit for dental use;

Fig. 2 is a section on an enlarged scale of the carbureter of Fig. 1; and

Fig. 3 is a section on the line III—III Fig. 2.

Foot bellows 1 may, through line 2, supply air under pressure. This pressure air line has branch 3 past adjustable valve 4 to carbureter 5. This carbureter 5 comprises a main lower chamber 6 having spiral wick 7 therein. Lateral extension 8 provides filling opening 9, which, when the liquid fuel, as gasoline, is supplied thereto may be closed 25 by cap 10. While the wicking 7 as attached to diaphragm or partition 11 tends to hold such against this top partition to form a tight tortuous or spiral way 12 over the liquid fuel or gasoline 13 therebelow, the 30 side walls of the wicking serve by capillary attraction to lift this liquid fuel. This wicking extends practically to the bottom of the chamber 7 so that the fuel may be used well down from one-half full without opening 35 a short circuit between the line 3 and the outlet 14.

The current of air from the pressure supply line 3 is in communication outside the spiral wicking 7 and such air tends largely 40 to travel along the spiral way, although some portions thereof may go through the wick walls. In either event this air travel serves to pick up the liquid fuel at a rate to enrich this air supply. This carbureted 45 fuel passes from the carbureter chamber 7 by opening 14 in the wood partition 11. This wood partition 11, while desirable for mounting the wicking 7, may not be as effective for isolating the chamber 7 from balancing or stabilizing chamber 15 and ac-

cordingly adjacent this partition 11 there may be placed a supplementary sheet metal partition 16.

In making this housing 5, such may be produced as a light weight structure for the 60 general housing, and this partition 16 be formed of light gage sheet metal as galvanized sheet iron. This duct 14 through the partition 11 passes into the balancing chamber 15 through opening 17 in the 65 partition 16.

The pressure supply line 2 has main portion 18 adjacent the branch 3 from which may flow past adjustable valve 19 air supply by way of line 20 disposed in the balancing 70 chamber 15 in a position over and in proximity sufficiently past the duct 14, 17, from the carbureter chamber 6 to have injector action in accelerating or drawing the fluid fuel into the balancing chamber 15. Remote 75 from this line 20 and preferably back from the outlet therefrom is discharge line 21, the flow of gas into which from the balancing chamber 15 may be adjusted by valve 22. This line 21 extends to burner 23 which is 80 preferably of a type having main or central supply 24 thereto as constant or non-adjustable, while valve 25 may adjust the flow of air and fuel in line 26 as an annular series 85 of jets about the central jet of the burner 23. Accordingly, by adjusting the valve 25 in the branch 26, the burner 23 may be changed from a slender or needle type of flame when this branch 26 is fully closed to a broader or fatter flame, as branch 26 is open. This 90 valve also adjusts the central needle flame. Accordingly, the burner has adjustments for reaching into or locating very minute places to heat or weld, as in a small place in a tooth, or back in a honeycomb radiator for 95 automobiles, or it may be opened out for a larger heating.

Adjustments at the burner at the carbureter or fluctuations in the pressure air supply, say as due to the intermissions in the pumping of the bellows 1 may be stabilized to work only gradual changes in the flame at the burner due to the mixing and stabilizing action of the supplemental chamber 15.

What is claimed and it is desired to secure 105 by United States Letters Patent is:—

1. A gaseous fuel mixture delivery means provided with a central delivery duct, a surrounding adjustable delivery duct, a mixing chamber from which the delivery 110

- ducts are supplied, a pressure air supply for the mixing chamber having branches in parallel, and a liquid fuel chamber in one of said branches. 35
- 5 2. A gaseous fuel mixture delivery means provided with two delivery ducts, one adjustable as to the other, a pressure air supply for the ducts, said supply having a branch, and a definite continuous course 10 duct-providing fuel supply in said branch, whereby there may be uninterrupted flow in each branch.
3. A gaseous fuel mixture delivery means provided with two delivery in parallel ducts, 15 one adjustable as to the other, a pressure air supply for the ducts, said supply having a branch, and a fuel supply in said branch, said fuel supply provided with an outlet and said pressure supply having an opening 20 adjacent said outlet for injector action upon the fuel supply.
4. A carbureter embodying a definite continuous open tortuous air passage as a liquid fuel reservoir providing a gaseous way over 25 the liquid fuel and provided with a fuel carrying air outlet from said way, and a pressure air line adjacent said outlet as an injector for accelerating the fuel laden air withdrawal from the way. 30
5. A carburetor embodying a wick chamber as a fuel reservoir, means providing a normal flow of a gas through the chamber to an outlet, and an injector disposed to provide a blast adjacent said outlet for accelerating fuel withdrawal from said chamber. 35
6. A carburetor embodying a fuel chamber, there being a wick in said chamber providing a definite continuous terminally open tortuous air way above the fuel with the chamber providing the remaining sides of 40 said way along said fuel, a second balancing chamber in communication with the first or fuel chamber, said second chamber coacting to stabilize fuel delivery, and a pressure air supply having a branch to each chamber. 45
7. A carburetor embodying a fuel chamber, there being a wick in said chamber providing a definite continuous terminally open tortuous air way above the fuel with the chamber providing the remaining sides of 50 said way along said fuel, a second balancing chamber in communication with the first or fuel chamber, said second chamber coacting to stabilize fuel delivery, and a pressure air supply having a branch to each chamber, said branch to the second chamber being disposed as to the communication between the chambers to accelerate flow from the first chamber into the second chamber. 55

In witness whereof I affix my signature.

WILLIAM E. WALDO.
